OUTBOARD MOTOR HOUSING

Elmer C. Kiekhaefer, Cedarburg, Wis.

Application June 16, 1955, Serial No. 36,539

Term of patent 14 years

(Cl. D71—1)

FIG.2.

Figure 1 is a perspective view of an outboard motor housing showing my new design, illustrating the front and one side thereof; and

The essential features of my design reside in the portions shown in full lines.

I claim:

The ornamental design for an outboard motor housing, as shown and described.
